United States Patent Office.

EBENEZER H. PLANT, OF PLANTSVILLE, CONNECTICUT.

Letters Patent No. 105,595, dated July 19, 1870.

IMPROVEMENT IN DIES FOR TRIMMING AND STRAIGHTENING AXLE-CLIPS.

The Schedule referred to in these Letters Patent and making part of the same.

To all whom it may concern:

Be it known that I, EBENEZER H. PLANT, of Plantsville, in the county of Hartford and State of Connecticut, have invented a new Improvement in Dies for Trimming and Straightening Axle-Clips; and I do hereby declare the following, when taken in connection with the accompanying drawings and the letters of reference marked thereon, to be a full, clear, and exact description of the same, and which said drawings constitute part of this specification, and represent in—

Figure 1, a top view of the lower or trimming-die; Figure 2, an end view of the trimming-die and follower;

Figure 3, a central section on line $z z$, illustrating the operation;

Figure 4, the clip as it comes from the forging-dies; and in

Figure 5, the same, after it comes from the trimming-dies.

This invention relates to the construction of dies for trimming and straightening carriage-clips.

In forging carriage-clips they are struck from round rods flattened over the central portion, and the ends left round for the bolts. In the process of striking up, the ends are naturally curved downward, as in fig. 4, and these require to be straightened, as in fig. 5. The surplus metal or fin upon the edge of the flat portion requires to be trimmed.

The object of my invention is to both trim and straighten the clip at the same operation, and consists in combining with the trimming-die a bed, onto

which, through the trimming-die, the clip will be forced by the follower, and, pressed by the follower onto the bed, will be straightened and brought into the desired shape.

A A are the two sides or cutting-edge of the trimming-die, fixed to a block, B, and made adjustable thereon.

C is a bed arranged below the cutters A A, and shaped as seen in fig. 3, corresponding to the under surface of the clip.

D is the follower, constructed so as to pass down between the cutters.

The blank, fig. 4, is placed in proper position over the cutters A A and the bed C. The follower D, brought down thereon, forces the clip through between the cutters, trimming off the surplus metal, and carrying it onto the bed C beneath, and, pressing it down onto the bed, straightens the clip, as seen in fig. 5, and thus, by a single operation, the clip is trimmed and straightened.

I have represented the bed C as an independent piece, and this I prefer, inasmuch as it may be adjusted for different-sized clips; but it is not essential, as it may be made a part of the block B.

I claim as my invention—

In combination with the trimming-die A A and its follower D, the bed C, constructed and operating substantially as described.

E. H. PLANT.
